Primary Examiner — Mitchell I. Siegel*(74) Attorney, Agent, or Firm* — Oliff PLC(57) **CLAIM**

The ornamental design for a textile machine, as shown and described.

DESCRIPTION

FIG. 1 is a front, left-side, top perspective view of the textile machine;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.

The broken lines depict parts of the textile machine that form no part of the claimed design.
